(57) **CLAIM**

The ornamental design for a cabin for work machine, as shown and described.

DESCRIPTION

FIG. 1 is a right side view of a cabin for work machine showing our new design;

FIG. 2 is a left side view thereof;

FIG. 3 is a front view thereof;

FIG. 4 is a rear view thereof;

FIG. 5 is top plan view thereof;

FIG. 6 is a right front perspective view thereof; and,

FIG. 7 is a right rear perspective view thereof.

Areas of the photographs shown in a coarse dot pattern and outlined in dashed lines illustrate a portion of the cabin for work machine that forms no part of the claimed design.
